UNITED STATES PATENT OFFICE.

CHARLES J. PETRASEK, OF NEW YORK, N. Y.

SELF-OILING ROTARY CUTTER.

1,421,713.

Specification of Letters Patent. Patented July 4, 1922.

Application filed February 3, 1921. Serial No. 442,108.

To all whom it may concern:

Be it known that I, CHARLES J. PETRASEK, a citizen of the United States, residing at New York city, borough of Manhattan, in the county of New York and State of New York, have invented certain new and useful Improvements in Self-Oiling Rotary Cutters, of which the following is a specification.

10 This invention relates to metal working appliances or tools, and has particular reference to means commonly used by plumbers, machinists, or the like, for cutting pipes, rods, or other materials, or the cutting 15 of threads on pipes, bolts, or the like.

Among the objects of the invention is to provide a cutting tool of the nature set forth above in which there is provided a self-contained chamber or holder for a lubricant such as oil to be applied from time to time as needed upon the cutting instrument, whereby the workman is relieved from the necessity of searching about for an oil can for this purpose.

25 Another object of the invention is to provide a rotary thread or pipe cutter comprising the usual head and one or more handles radiating therefrom, one of the handles serving as an oil container and provided with valves at its opposite ends to control the inflow of air as well as admission of oil, and also for the control of the delivery of the oil from the container.

With the foregoing and other objects in view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a front elevation of the principal parts of my improvement, parts being broken away.

Fig. 2 is a vertical section on the line 2—2 of Fig. 1.

50 Fig. 3 is a detail of a modification of valve mechanism.

Referring now more specifically to the drawings, I show a cutter head 10 of any usual or conventional design or construction, the same being provided with a central hub 11 fitted with a bearing sleeve 12

around its axis, and on opposite sides of the axis are provided cutting bits 13 for acting upon metal to be threaded or cut. These parts being conventional, no special description thereof is necessary, and consequently it is to be understood in this connection that I do not propose to be limited unnecessarily in the application of my invention to any particular form or type of cutting tool.

14 indicates one or more handle sockets ordinarily made as integral parts of the body 10, and in which handles 15 and 16 are fitted in any well known manner for the manipulation of the cutting tool.

Without special reference therefore to the handle 15, handle 16 is a tubular or hollow body in the nature of a piece of gas pipe tapped into one of the sockets 14. Leading from the interior of the socket 14 is a port 17 communicating with the interior of the head adjacent to the bits 13. The handle 16 may be referred to hereinafter as an oil receptacle. Tapped into the inner end of the receptacle 16 is a plug 18 constituting a valve seat or closure in co-operation with valve 19 closing outward against the plug. To the valve 19 and extending outward laterally therefrom through a slot 20 is a finger piece 21 within easy reach of the operator's thumb or finger at any time. The outer end of the receptacle 16 is threaded interiorly at 22 and inward from the extreme end so as to accommodate two plugs 23 and 24. The inner plug 23 constitutes an abutment 90

for a heavy spring 25 bearing against the outer end thereof and is provided with a hole 23' through which projects inward a bolt 26 having on its outer end a nut or head 27 threaded down beyond the extreme outer end 95 thereof, leaving a stud 28 on the outside of the nut. The nut bears against the outer end of the heavy spring 25 and so the spring tends to project the bolt outward through the hole 23'.

To the valve 19 is attached a bolt 29 projecting outward through a hole 18' in the plug 18. The bolts 26 and 29 are provided with holes in their free ends, and a wire 30 or similar connection is extended through said holes serving to link the bolts 100 together for conjoint movement. Hence, the action of the spring 25 serves normally to hold the valve 19 closed, preventing a discharge of oil from the receptacle. When, however, the operator wishes to supply one 105 or more drops of oil to his work, he will stop the cutter with the receptacle 16 up-

110

right and depress the finger piece as much as necessary to give him the amount of oil required. This action is, of course, against the force of the spring 25 which acts automatically to close the valve 19 when the finger piece is released.

The plug 24 when removed provides a means to supply a fresh charge of oil into the receptacle and when replaced in the 10 position shown it acts as a closure for the outer end of the receptacle in connection with a valve 31. The plug is provided with an air vent 32 which is sealed by the valve 31 by virtue of a light spring 33 interposed 15 between the nut 27 and the valve 31 and seated upon the stud 28. When the valve 19 is open as above described for the delivery of oil from the receptacle the nut 27 as well as all the other parts associated 20 with the tie member will be drawn inward, and hence the valve 31 is relatively free to open to admit air into the receptacle because the spring 33 is so relatively light or weak. Hence, there is no impediment to the 25 outflow of oil from the receptacle because of external atmospheric pressure which might result if no air vent were provided.

The plug 24 is provided at its outer end with a plurality of projections 34 serving 30 to guard the vent 32 and prevent the clogging up thereof by dirt or the like. It will be noted that not only does this appliance provide a convenient and reliable means for oiling a cutting device for this rotary appliance, but also it is always accessible for 35 use as an oil can for oiling any other machine, it being only necessary to unscrew it from its socket 14 for this purpose. To detach the receptacle from its socket it is but necessary to unscrew it and then tilt it laterally to remove the finger piece inward through the slot 20. Obviously the oil, instead of passing through the port 17, may be 40 conveyed in any suitable direction along a duct leading either inside or along the outside of the head to the bits or cutting devices. 45

The finger piece 21 in the main figures is shown swiveled upon the valve 19, so that 50 while the finger piece is held in the slot 20 during the rotation of the member 16 into and out of its socket 14 the valve may remain stationary with respect to the valve seat or receptacle. As indicated, however, in Fig. 3 the finger piece 21' may be formed 55 integral with the valve 19', and instead of

a wire or other similar connection 30 between the two bolts 26 and 29, a single bolt or rod 29' may be employed. Obviously in this form of the invention the valve must remain stationary with the finger piece 60 while the receptacle 16 rotates relatively. No objection, however, results since the parts between which there is relative movement are always well lubricated.

I claim:

1. The combination with a rotary cutter head formed with an oil port through the side thereof, of an oil receptacle carried by the head adjacent to said port, said receptacle having a valve seat at the end adjacent to the port, a valve co-operating with said valve seat, and a finger piece extending laterally from said valve for manipulating the valve and at an angle to the axis thereof. 75
2. A device as set forth in claim 1 in which the valve is self closing and the finger piece serves to open the same. 70
3. The combination of a rotary cutter head formed with a lateral oil port, a combined handle and oil receptacle connected to the head just outside of said port, and means to cause the delivery of oil from the receptacle through said port, said oil delivery means comprising a valve and a finger piece 80 projecting at right angles to the axis of the valve, there being provided a slot through the side of the cutter head through which said finger piece projects substantially as set forth. 85
4. The herein described oil receptacle comprising a hollow body, a plug for the delivery end of the body, a bolt projecting inward through said plug, a valve connected to the bolt and co-operating with the outer 90 face of the plug, a finger piece projecting laterally from the valve, a pair of spaced plugs carried by the opposite end of the body, a bolt projecting through the inner one of these two valves, a heavy spring co-operating between the latter mentioned bolt and its plug serving to project the bolt outward, a tie member extending between the two plugs, a valve co-operating with the inner face of the outer plug of the pair of 95 plugs, and a light spring located between the second mentioned bolt and the latter mentioned valve, substantially as set forth. 100
5. The herein described oil receptacle comprising a hollow body, a plug for the delivery end of the body, a bolt projecting inward through said plug, a valve connected to the bolt and co-operating with the outer face of the plug, a finger piece projecting laterally from the valve, a pair of spaced plugs carried by the opposite end of the body, a bolt projecting through the inner one of these two valves, a heavy spring co-operating between the latter mentioned bolt and its plug serving to project the bolt outward, a tie member extending between the two plugs, a valve co-operating with the inner face of the outer plug of the pair of plugs, and a light spring located between the second mentioned bolt and the latter mentioned valve, substantially as set forth. 105

In testimony whereof I affix my signature.

CHARLES J. PETRASEK.
